UNITED STATES PATENT OFFICE

FRANK W. GRISWOLD, OF MINNEAPOLIS, MINNESOTA

YIELDING SELF-ARIGHTING LAMP OR SIGNAL DEVICE

Application filed March 3, 1924, Serial No. 696,545. Renewed April 9, 1930.

This invention relates to a semaphore or signal post or lamp post, and while the invention is applicable to any such post or semaphore device the same is more particularly designed as a traffic signal post. With the large volume of automobile traffic in cities it is necessary to have some traffic regulator at the street intersections. As there are car tracks at a great many of such intersections it is desirable to have a signal device which can be disposed between the double car tracks on the street. It is also desirable to have a signal device which is capable of yielding so that if the same is struck by a vehicle the post and vehicle will not be greatly damaged. It is also necessary that such a semaphore be constructed so that the signals thereon can be clearly read either day or night and so that said signals will not be unduly affected by the rays of the sun in the daytime.

It is an object of this invention, therefore, to provide a signal post so mounted that if the same is struck and knocked to one side it will resume its vertical position.

It is a further object of the invention to provide a stop means, or centering means for insuring that the post will resume a true vertical position.

It is another object of the invention to provide a signal device having a hollow standard with opaque means therein dividing the same into chambers so that the rays of the sun or other light cannot shine through said standard.

It is still another object of the invention to have a signal device having a hollow standard, the sides of said standard having panels therein with characters cut therefrom, together with panels of material which is permeable to light and the outer one of which has a ground glass surface.

It is still a further object of the invention to provide a signal device comprising a hollow standard divided into a plurality of chambers with light producing means therein, said standard having an opening therethrough from top to bottom for the circulation of air.

It is also another object of the invention to provide a signal device having a standard

with four sides arranged at right angles to each other, which sides are provided with traffic directing characters and portions.

It is, furthermore, an object of the present invention to provide such a signal device having a vertical standard with a substantial spherical ball at its base yieldingly supported upon centering means, the supporting means and righting means for said standard and ball being disposed in a chamber below the surface of the ground.

These and other objects and advantages of the invention will be fully set forth in the following description made in connection with the accompanying drawings in which like reference characters refer to the same parts throughout the different views and in which,

Fig. 1 is, for the most part, a vertical section through the lower portion of the signal device;

Fig. 2 is a view in side elevation of the upper portion of the signal device with the lower part thereof in vertical section, the signal device being viewed from one of the corners thereof;

Fig. 3 is a vertical section taken on the line 3—3 of Fig. 2, as indicated by the arrows;

Fig. 4 is a horizontal section taken on the line 4—4 of Fig. 1, as indicated by the arrows;

Fig. 5 is a horizontal section taken on the line 5—5 of Fig. 1, as indicated by the arrows;

Fig. 6 is a view in side elevation of a lower plate used;

Fig. 7 is a view in side elevation of an upper plate used;

Fig. 8 is a view in horizontal section taken on the line 8—8 of Fig. 3, as indicated by the arrows, the same being shown on an enlarged scale;

Fig. 9 is a vertical section taken on the line 9—9 of Fig. 8;

Fig. 10 is a vertical section on the line 10—10 of Fig. 2, as indicated by the arrows, Figs. 9 and 10 being shown on an enlarged scale;

Fig. 11 is a top plan view, partly in horizontal section, of Fig. 2;

Fig. 12 is a view in vertical section taken on the line 12—12 of Fig. 11; and

Fig. 13 is a partial vertical section similar to Fig. 1 shown on an enlarged scale.

Referring to the drawings, the signal device comprises a standard 1 which is secured at its bottom to a semi-spherical or partly spherical ball or member 2. The standard 1 comprises four sides arranged substantially at right angles to each other, and while such four sides will usually be necessary, with or without other sides, in the embodiment of the invention illustrated, a substantially square standard is shown comprising four corner posts 3. These posts 3 have studs 3^a at their lower portions projecting through the top flange 2^a of the ball 2 and firmly secured therein by nuts on said studs. A cap 4 having a pyramidal top surface surmounts the tops of the corner posts 3 and is secured by cap bolts passing through the holes 4^a into the top one of a series of plates 5 which are secured to and between said corner posts. The cap 4, as shown in Figs. 11 and 12 is of hollow construction and has inwardly extending ribs 4^b at each corner formed with right angular sides at their inner ends. A pair of panels 6 are disposed against and extended between said sides at the inner ends of said ribs, said panels being secured to said ribs by suitable small bolts or rivets passing through holes 6^a in said panels. It will be noted that the cap 4 has openings 4^c at each side thereof, the panels 6 being alined with and extending somewhat above said openings. The inner sides of the posts 3 have square or rectangular portions 3^b with sides at right angles to each other forming a square corner and the plates 5 are of square formation with their corners recessed to fit over the inner corners of the post 3, said plates 5 having circular openings extending centrally therethrough. Said plates 5 are secured to the corner posts 3 by the bolts or rivets 7 extending radially through the posts 3 and said plates, as clearly shown in Figs. 8 and 9. Disposed above and beneath the two lower plates 5 are semi-circular plates 8, said latter plates comprising somewhat more than a half circle and, as clearly shown in Fig. 8, these plates are reversely and oppositely arranged above and below said plates 5 so that a zigzag passage is formed through the plates 5. Vertical diagonally disposed plates 9 extend between the plates 5 and divide the standard into two vertically extending chambers, which chambers are further divided by the two lower plates 5. The plates 9, at their outer ends, are bent substantially at 45 degrees to fit against the sides of the corner posts 3 and are held in position and clamped to said post by small plates 10 also bent substantially at 45 degrees to fit against the adjacent sides of the corner posts 3, which plates 10 are bolted or riveted to the plates 9. Se-

cured to the plates 9 in uniformly spaced relation vertically thereof are angle plates 11 having their longitudinal center lines extending diagonally of the standard and said plates 11 have secured thereto and depending therefrom, lamp sockets 12 carrying the lamps 13. A lamp socket 12^a is also disposed above the upper plates 11 carrying a lamp 13^a disposed centrally of the cap 4. An angle plate 14 is secured to one of the side panels of the standard below the lower plate 5 and carries a lamp socket 12^b having therein a lamp 13^b.

Secured against the outer sides of the square portion 3^b of the post 3 are panels 16, 17 and 18. The inner panel 16 is of colored transparent material, preferably red or green, the same being indicated as red in Fig. 10. The intermediate panel 17 is of translucent material and preferably provided with a ground glass surface. The outer panel 18 is opaque and, as shown in Fig. 2, two of the upper panels 18 have cut therein the characters G O forming the word Go, while the two alternate panels have the characters cut therefrom forming the word Stop. The panels 16 and 17 above and below the intermediate plate 5 are the same, but the outer panels 18^a below the intermediate plate 5 have, in addition to the words Go and Stop already described, small apertures 18^b cut therethrough, which apertures aline with the lamp 13^b. Below the upper panels 18 the post is provided with other outer panels 18^c. These panels, in the embodiment of the invention illustrated, have cut therefrom the characters forming the words "No left turn." The inner panels 17 preferably extend throughout the length of the standard. The panels 16, however, are of different colors for the different words, the same being of red under the panels having the word "Stop" and the lower panels having the words "No left turn", but being preferably green under the word "Go". The panels 16 in alinement with or behind the openings 18^b also are preferably red.

The means for yieldingly supporting and for righting the post may be arranged in any convenient and suitable manner, but in the embodiment of the invention illustrated, the same are shown as carried by a cylindrical shell 20 preferably of metal and set into a concrete mounting 21 surrounding the same, into which mounting angle plates 22 riveted to the outside of the shell adjacent its top preferably project. It will be noted that the top of the concrete mounting 21 is flush with the top of the street pavement 23. Secured to the inner side of the shell 20 adjacent the top thereof and as illustrated, in line with the angle plates 22 and by the same rivets holding said plates are a series of circumferentially spaced angle brackets 24. The inwardly projecting flanges 24^a of said

brackets are slotted to receive headed and nutted bolts passing through the flanges 25^a on the rib carrying members 25. The members 25 have inwardly projecting radially disposed ribs 25^b, the inner faces of said ribs being curved and having convex surfaces, said ribs also having flat top surfaces outwardly of said curved surfaces. The ball 2 is provided with a groove 2^b (see Fig. 13), the outer surface of which is concave in cross section fitting and conforming to the convex surface of the ribs 25^b. The groove 2^b forms a shoulder 2^c on the ball 2, said shoulder normally engaging the inner or upper portion of the ribs 25^b. While the groove 2^b could be cut in the ball 2 and extend therearound, in the embodiment of the invention illustrated, the ball is formed of somewhat reduced diameter at its lower portion, which reduced portion merges into the lower edge of the groove 2^b. The ribs 25^b are provided at their top surface with tapped holes, and a cover plate 26 having a central opening surrounding ball 2 and sloping outwardly and downwardly from said opening, is secured to said ribs by cap screws 27 disposed in radial slots in said cover plate and screwed into said tapped holes. The cover plate 26 is provided with a yielding gasket 28 secured adjacent the central opening therein and projecting inwardly and contacting with the sides of the ball 2. Headed and threaded screws 19 project into the outer sides of the members 25 and are provided with nuts 19^a which engage the outer side of the member 25 and the heads of said screws engage the inner side of the shell 20 and abut thereagainst preventing outward movement of the members 25. The lower portion of the ball 2 has an inwardly projecting sleeve 2^d centrally disposed therein, the opening through which flares at its outer end to form curved surfaces merging with the outer surface of the ball 2. A rope clamp formed by spaced plates 29 connected by headed and nutted bolts 30 is disposed at the top of the sleeve 2^d and clamped to one end of a hollow flexible cable 31 preferably of wire rope, which cable extends downwardly through the opening in sleeve 2^d some distance into the shell 20 where its lower end is clamped between plates 32 pierced by headed and nutted bolts 33, the lower side of one of said plates having a yoke 33^a depending therefrom. As stated, the cable 31 is hollow and a plurality of electrical conductors 34 extend therethrough being connected at their upper ends in appropriate relation to the lamps 13, 12^a and 13^b. Said conductors pass out at the lower end of the cable 31 and into a conduit 35 projecting from and through the side of shell 20, said conductors leading to some suitable source of electrical energy.

A plate 36 (see Figs. 1 and 7) of rectangular form, has a substantially centrally dis-

posed hook 36^a at its upper side engaged with the yoke 33^a. The plate 36 is provided with a plurality of slots 36^b arranged in the form of a square about its sides, as shown in Fig. 5 through which project upwardly the eyelets or loops 37^a formed on the upper ends of a series of springs 37. Rods 38 and 39 extend through the eyelets or loops 37^a and are held from movement by the cotter pins 39^a secured therein. A lower plate 40 (see Figs. 1 and 6) also of substantially rectangular form, is spaced below plate 36 and arranged with similar slots 40^a through which pass loops formed on the lower ends of the springs 37, said loops being held in place by rods 41 and rods therebetween similar to the rods 39, but not shown, which rods are also held in place by suitable cotter pins. Plate 40 has a downwardly extending yoke 40^b thereon which is engaged with a hook 42 projecting upwardly from a transverse angle bar 43 extending across the shell 20 and having its flanges contacting and riveted to the sides of said shell.

The cable 31 intermediate the ball 2 and the clamp 32 and adjacent said ball passes through a central aperture in a plate 44, which is provided with a series of circumferentially arranged headed and nutted bolts 45 passing through and securing to said plate, loops or eyelets formed at the inner ends of a series of tensile springs 46. Said springs also have loops or eyelets formed at the outer ends which are engaged over hooks 47 secured in the sides of the shell 20 and projecting radially inward.

In operation, the signal lamp post will be mounted in a desired location, as shown and described. The signal illustrated is designed to direct the traffic at a street intersection. A clock-controlled switch (not shown) is provided by which, automatically, the lamps 13 in the chamber above the middle plate 5 are lighted alternately with the lamps in the chamber below said middle plate. Just before the lights change in the two chambers the bottom light 13^b is lighted to illuminate the apertures 18^b which indicates that the signal and traffic are about to change. The top lamp 13^a, preferably, is constantly lighted so that the apertures 4^c in the cap 4 are continuously illuminated. With a signal of the type described and such as shown in applicant's prior Patent 1,461,116, granted July 10, 1923, it was found in practice that the rays from the sun would shine through the standard and interfere with the proper reading of the signals. The diagonal partition 9 is therefore provided in applicant's device so that the sun cannot shine through the sides of the device and illuminate the opposite sides and thus improperly illuminate the signal letters thereon. It was also found that when the sun shone against the letters they would reflect light and be improperly illuminated.

so that it was sometimes difficult to tell whether the words were illuminated by the interior lamps 13 or not. In order to overcome this difficulty the intermediate plates 17 were provided. These intermediate plates 17 have a ground glass effect on their outer surfaces, so that, when the lamps 13 are extinguished, this surface is visible through the cut-out characters and shows white or dull. 10 Also, the sun therefore cannot shine on the colored inner panel 16 and illuminate the same to cause the letters to appear as if illuminated by the interior lamps 13. When the lamps 13 are lighted the colored panel 15 16 readily shows through the panel 17 so that the proper colored illumination is given. The characters in the outer panels are highly illuminated by the interior lamps 13, 13^a and 13^b and stand out emphatically so that the 20 same can be seen at a great distance. The illumination is in no way interfered with by the interposition of the intermediate panels 17. It is desirable to have a current of air passing through the standard to exert a cooling effect thereon and counteract the heat of the lamps 13, 13^a and 13^b. It will be seen that the air can pass into the standard through the cable opening in sleeve 2^a of ball 2 and can pass around the plates 8 up to and 25 out through the openings 4^c in cap 4.

It is very desirable to have the signal standard yieldingly supported and the standard herein disclosed can be struck or pushed down into contact with the paving and will immediately aright itself. When the post is 35 pushed down or to one side, the ball 2 merely turns on the bearing surfaces of the ribs 25^b. The vertical springs 37 in applicant's device will normally be under considerable tension 40 and the horizontal springs 46 will be under some tension. The groove 2^b which fits the convex surface of the ribs 25^b, together with said springs, has a centering effect on the ball and as the ball nears its central position 45 it will snap into the central position with the standard 1 in a true vertical position. The shoulder 2^c therefore forms a centering stop and the groove 2^b, together with the springs 37 and 46, form a centering means. It was 50 found in practice with applicant's device having the construction as shown in his prior patent above cited that when the standard had been pushed down it would not always come back to a true vertical. This difficulty 55 has been overcome by the present structure. The convex surface of the ribs 25^b also insures a small contacting surface with the ball when the same is moved from its central position. The rounded surface of the ball adjacent the 60 cable 31 prevents abrasion of the cable. The cover 26 effectively prevents dirt entering the shell 20 at the sides thereof or at its central portion. It will be seen that the members 25 and the cover 26 will be adjusted as desired 65 to center and properly position the ball 2.

The screws 19 with the nuts thereon may be manipulated to center ball 2 and when adjusted will prevent outward movement of the members 25.

In modern traffic it is often necessary for a 70 vehicle to swerve to one side to avoid a collision and this is especially true where the fire department makes runs through the city. The present signal device will, as stated, yield to any considerable pressure, so that 75 great damage will not be done, if a vehicle collides therewith. It often happens that the lighting service is cut off for one or more hours even in the largest cities. A signal standing at a street intersection or in the middle of the street is very apt to be struck by vehicles, if all the street lights are extinguished and the signal is dark. With the present signal such a collision in the darkness will not cause any appreciable damage. 80

85 From the above description it is seen that applicant has provided a simple and improved signal device. The parts thereof are simply and inexpensively constructed and yet are very durable and function to attain 90 improved results.

95 It will, of course, be understood, that various changes may be made in the form, details, arrangement and proportions of the parts without departing from the scope of applicant's invention, which, generally stated, consists in a device capable of carrying out the objects above set forth, such as shown and described and defined in the appended claims.

100 What is claimed is:

1. A lamp or signal device having in combination, a standard, a member secured to the bottom of said standard having a substantially semi-spherical underside, a plurality of circumferentially spaced supports for said member having convexly curved supporting surfaces with which said member constantly engages and over which it slides, said member having a shoulder formed in its underside shaped to fit said convex surfaces and rest in engagement therewith to form a stop when said standard is in vertical position, and resilient means holding said member in position with said standard vertical. 110

115 2. A lamp or signal device comprising a standard, a substantially spherical ball at the bottom thereof, spaced radially disposed supports for said ball having convex supporting surfaces, said ball having an annular groove cut therein concave in radial cross section and formed on the same curvature as said convex surfaces, said groove fitting said convex surfaces and forming a shoulder with the upper portion of the ball which contacts said convex surface, said shoulder constituting a stop for said ball when said standard is in vertical position, and means tending to move said standard to vertical position whereby said groove will snap into position in contact with 120

125

130

said supports and prevent vibration of said standard and leaning thereof.

3. The structure set forth in claim 2, said supports being disposed below the horizontal central plane of said ball.

4. The structure set forth in claim 2, the diameter of said ball below said groove being reduced and merging into the surface of said groove.

5. A lamp or signal device comprising a standard having a partly spherical ball at its lower end, supporting means for said ball, said ball having an aperture extending centrally therein at its bottom, a flexible cable disposed in said aperture and secured in said ball, a member through which said cable passes below and adjacent said ball, a plurality of radially disposed and substantially horizontal springs secured to said member and fixedly secured at their outer ends, and resilient means normally under tension to pull downwardly on said cable.

6. A lamp or signal device comprising a cylindrical casing adapted to be set in the ground, a plurality of circumferentially spaced brackets secured to the inner wall of said casing, said brackets having inwardly projecting ribs thereon provided with convex surfaces, a standard carrying a member at its lower end having a spherical surface supported on said ribs, and means in said casing holding said member in contact with said ribs.

7. The structure set forth in claim 6, said ribs being adjustable inwardly and having thrust means at their outer sides abutting the inner wall of said casing.

8. The structure set forth in claim 6, a cover for said casing surrounding and engaging said member and secured to said ribs, said cover having means for radial adjustment.

9. A lamp or signal device comprising a hollow standard having four sides, a partition extending diagonally of said standard forming two chambers therein, a source of light in each of said chambers, panels permeable to light in the sides of said standard, one of which has a ground glass surface and one of which is colored, and an opaque plate at the outer side of said panels having characters cut therefrom.

10. A lamp or signal device comprising a hollow standard having four sides, an opaque partition extending diagonally thereof forming two chambers therein, a transverse opaque partition dividing each of said chambers into upper and lower sections, plates at the four sides of each chamber, similar traffic directing words cut from the oppositely disposed plates, the words on adjacent plates being different and backed by differently colored transparent material, and an illuminating means in each of said chamber sections.

11. The structure set forth in claim 10, and

a chamber below said chambers and illuminating means therein, said panels having apertures therethrough in alignment with said means, said apertures being backed by a transparent colored material.

12. A lamp or signal device comprising a hollow standard having four sides, a lamp in said standard, a plate in the side of said standard having characters cut therefrom, a sheet of brightly colored material appearing illuminated through said characters when said lamp is lighted and a sheet of material of a different and dull color appearing through said characters when said lamp is not lighted.

13. A lamp or signal device comprising a hollow standard having four sides, a lamp in said standard, a plate in the side of said standard having characters cut therefrom, a sheet of material permeable to light at the inner side of said plate having a ground glass surface thereon adjacent said plate, and a sheet of colored transparent material at the inner side of said latter sheet whereby when said lamp is not lighted the ground glass surface will show through said characters but when the lamp is lighted the colored sheet of material will be illuminated and show through said characters.

14. A lamp or signal device comprising a hollow standard, a vertically extending partition dividing said standard into chambers, lamps in said chambers, means for supporting said standard for downward swinging movement in any direction, flexible means holding said standard in vertical position, said standard having an opening at its top, a passage extending longitudinally therethrough and having an opening at its bottom, said flexible means passing through said last mentioned opening, said openings and passage permitting entrance and circulation of air through said standard caused by the heat of said lamps.

15. A signal device comprising a standard, a supporting member secured to the bottom thereof having a convex lower surface and having an aperture extending therethrough, supporting means for said member, a flexible cable passing through said aperture and secured to said member and extending downwardly therefrom, a resilient means connected to the lower end of said cable for maintaining said standard in vertical position when swung down and restoring it to vertical position, and electrical conductors enclosed in said cable and passing into said member and standard.

16. The structure set forth in claim 15, a plate through which said cable extends, and a plurality of radially disposed springs connected to said plate and having their outer ends fixed, said springs tending to hold said plate in central position.

17. The structure set forth in claim 15,

115

120

125

130

said resilient means comprising a series of vertically disposed springs, a pair of substantially horizontal spaced plates between which said springs extend and to which they are connected, means connecting the upper plate to said cable, and means for anchoring the lower plate in stationary position.

18. A lamp or signal device comprising a cylindrical casing adapted to be set in the ground, a plurality of circumferentially spaced brackets secured to the inner wall of said casing, said brackets having inwardly projecting ribs thereon provided with convex surfaces, a standard carrying a member at its lower end having a spherical surface supported on said ribs, and a centering means for said ball and ribs engaging the latter and said casing.

19. The structure set forth in claim 18, said last mentioned means comprising headed screws engaging said ribs and abutting against said shell at their outer ends.

20. A lamp or signal device comprising a hollow standard, a partition dividing said standard into chambers, said standard having openings at the top of said chambers, lamps in said chambers, means for supporting said standard in vertical position, said standard having a supporting member at its lower end adapted to be moved in various directions with a chamber therein communicating with said chambers, said member having a passage leading from the chamber therein through its bottom, a flexible cable having conductors therein passing through said passage to said lamps, said opening and chambers also permitting a circulation of air upward through said standard caused by the heat of said lamps and means connected to said cable for maintaining said standard normally in vertical position and restoring the same to vertical position when swung down.

21. A lamp or signal device comprising a standard, a substantially spherical ball at the bottom thereof, supporting means for said ball at the underside thereof, and a cover plate surrounding said ball having means contacting the same, and means for holding said cover plate in various positions.

22. A lamp or signal device comprising a standard, a universally oscillatable means at the bottom thereof, supporting means for said oscillatable means, a casing set into the ground below said oscillatable means carrying said supporting means, means in said casing for holding said oscillatable means in contact with said supporting means with said standard erect, an annular cover plate surrounding said oscillatable means, an annular gasket on said plate contacting said oscillatable means, and means permitting movement of said plate and holding it in various positions.

23. A lamp or signal device comprising a standard, a substantially spherical hollow

ball at the bottom thereof, said ball having an opening at its underside, supporting means for said ball at the underside thereof, a flexible means passing into said opening, means disposed in said ball secured to said flexible means and engaging said ball for connecting the same and said flexible means, and resilient means connected to said flexible means for holding said ball on said supporting means with said standard in vertical position.

24. A lamp or signal device having in combination, a hollow post, electrical lamps therein, a swivelling member at the bottom of said post adapted to oscillate with said post in various circumferential planes, supporting means for said member, a cable secured to the bottom of said member, anchored resilient means secured to said cable holding said member to its support in upright position, and conductors for said lamps passing through said cable and member into said post.

25. A lamp or signal device comprising a standard, a substantially spherical ball at the bottom thereof, supporting means for said ball at the underside thereof, a flexible cable secured to and extending from the bottom of said ball, resilient means secured at the lower end of said cable for holding said ball on said supporting means with said standard in vertical position, a comparatively thin member surrounding said cable between said resilient means and ball through which said cable is freely movable, and a plurality of radially disposed resilient means secured to said member and extending therefrom and fixedly secured at their outer ends.

26. A signal device having in combination, a hollow standard, a member having a lower convex surface at the bottom of said standard and having a central opening through said surface, a plurality of circumferentially spaced supporting means for said member, a flexible cable secured to said member and extending downwardly through said opening, resilient means connected to said cable adapted to maintain said standard in vertical position and restore the same to vertical position when swung downwardly, electrically controlled signal devices in said standard and electrical conductors passing through said cable and into said standard for controlling said signal devices.

27. A street intersection signal device having in combination, a narrow post substantially square in cross section with substantially straight vertically extending corners, signal characters carried by said post and arranged in vertical rows, said post having openings in the sides thereof through which said characters are visible, a supporting member at the base of said standard having a lower convex surface with a central opening

therethrough, means supporting said member and having a convex surface engaging said convex surface, a flexible cable secured to said supporting member, resilient means connected to said cable to maintain said standard in vertical position and restore it to vertical position, and electrical conductors conerolling said signal characters passing through said cable and into said supporting member and standard.

28. A signal device adapted to be disposed at the intersection of two thoroughfares comprising a normally vertically extending hollow standard of substantially uniform transverse dimensions from top to bottom and of a width sufficiently small so that the standard can be disposed between adjacent street car tracks spaced to give standard clearance between oppositely moving cars without interference with said cars, said standard presenting sides facing in four directions so as to respectively face said thoroughfares with alternate sides disposed directly opposite one another, means for simultaneously illuminating and displaying indicia at two opposite sides of said standard to direct the restraint of traffic on one of said thoroughfares and for simultaneously illuminating and displaying indicia at the other two sides of said standard to direct the passage of traffic on the other of said thoroughfares and vice versa, supporting means at the base of said standard, supporting elements cooperating with said supporting means and arranged to permit it to move in any direction and means to normally hold said standard in vertical position while permitting it to be depressed substantially in contact with the street when said standard is contacted by a vehicle and to restore it to vertical position after being depressed.

In testimony whereof I affix my signature.

FRANK W. GRISWOLD.
